(57) CLAIM

The ornamental design for a chair, as shown and described.

DESCRIPTION

FIG. 1 is a first perspective view of a chair in accordance with the new design;

FIG. 2 is a second perspective view of the chair of FIG. 1;

FIG. 3 is a front view of the chair of FIG. 1;

FIG. 4 is a rear view of the chair of FIG. 1; and,

FIG. 5 is a right side view of the chair of FIG. 1, the left side being a mirror image.

In the drawings, the broken lines illustrate portions of the chair that form no part of the claimed design.

1 Claim, 5 Drawing Sheets
